(57) **CLAIM**

The ornamental design for a housing module, as shown and described.

DESCRIPTION

FIG. 1 is a front perspective view of the housing module showing our new design.

FIG. 2 is a perspective view from the top-left side of the design shown in FIG. 1; and,

FIG. 3 is a perspective view from the top-right side of the design shown in FIG. 1.

The bottom of the housing module forms no part of the claimed design.
